US0D1021654S

(12) **United States Design Patent** (10) Patent No.: **US D1,021,654 S**
(45) Date of Patent: ** Apr. 9, 2024

(54) **PORTABLE VEHICLE DIAGNOSTIC DEVICE**

(71) Applicant: **AUTEL INTELLIGENT TECHNOLOGY CORP., LTD.**,
Guangdong (CN)

(72) Inventors: **Yongshuai Wang**, Guangdong (CN);
Yuelong Liao, Guangdong (CN)

(73) Assignee: **AUTEL INTELLIGENT TECHNOLOGY CORP., LTD.**,
Guangdong (CN)

(**) Term: **15 Years**

(21) Appl. No.: **29/796,489**

(22) Filed: **Jun. 24, 2021**

(30) **Foreign Application Priority Data**

Dec. 24, 2020 (CN) 202030800873.7

(51) LOC (14) Cl. **10-04**

(52) U.S. Cl. **D10/78**
USPC .....

(58) **Field of Classification Search**

USPC D10/47, 74, 75-78, 80, 81; D14/203.7;
D13/124

CPC .. G01R 31/006; G01R 31/007; G01R 31/392;
G01R 31/367; G01R 31/36

Primary Examiner — George D. Kirschbaum

Assistant Examiner — Antoinette Martine Suiter

(57) **CLAIM**

We claim the ornamental design for a portable vehicle diagnostic device, as shown and described.

DESCRIPTION

FIG. 1 is a front elevational view of a portable vehicle diagnostic device showing our new design;

FIG. 2 is a back elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a first perspective view thereof; and,

FIG. 8 is a second perspective view thereof.

1 Claim, 7 Drawing Sheets
